UNITED STATES PATENT OFFICE

LOUIS MARX, OF NEW YORK, N. Y., ASSIGNOR TO CHARLES J. CORRELL AND FREEMAN F. GOSDEN, BOTH OF CHICAGO, ILLINOIS

DESIGN FOR A FIGURE TOY

Application filed March 12, 1931. Serial No. 39,041. Term of patent 14 years.

To all whom it may concern:

Be it known that I, LOUIS MARX, a citizen of the United States, residing in the city, county, and State of New York, have invented a new, original, and ornamental Design for a Figure Toy, of which the following is a specification, reference being had to the accompanying drawing, forming a part thereof, wherein the figure is a perspective view of a figure toy showing my new design.

I claim:

The ornamental design for a figure toy, substantially as shown.

LOUIS MARX.
